Pierre Barnes
ATTORNEY

UNITED STATES PATENT OFFICE

RICHARD GREVSTAD, OF OLALLA, WASHINGTON

TARRING MACHINE

Application filed February 19, 1929. Serial No. 341,174.

This invention relates to apparatus for applying a preservative such as tar, pitch, or the like, to thread, cord, fishing lines, etc.

The object of my invention is the provision of apparatus of this character which will be of inexpensive construction, and convenient to operate, affording structure adapted to obviate the heretofore annoying direct contact with the preservative, the invention being peculiarly effective to its use in exposed situations in any atmospheric conditions.

The invention consists in a pot in which the preservative is heated and maintained at a condition of fluidity suitable for treating an article, a means to cause the article to be progressively dipped in the preservative material and eventually wound compactly about a spool from which pieces of the article may be withdrawn for use. The invention further consists in the novel construction, arrangement and combination of parts hereinafter described and claimed.

In the accompanying drawings, Figure 1 is a plan view of apparatus embodying my invention; Fig. 2 is a view partly in side elevation and partly in longitudinal vertical section of Fig. 1; and Fig. 3 is a detail transverse sectional view through 3-3 of Fig. 2.

As shown in the drawings the frame of the machine comprises a base 5, which may be of wood, and serving as a support for standards 6 and 7 located near the opposite ends of the base and also for the legs 8 of an open vessel or pot 9 located between said standards. Said legs are rigidly secured to the pot about its periphery and have their lower ends turned outwardly to serve as feet 10 through which extend screws 11 whereby the pot holding legs are secured to the base.

The pot 9 is supported at an elevation to accommodate a lamp stove 12 therebelow in which fuel oil is burned to generate heat to liquefy the material, hereinafter termed tar, indicated by 13 in Fig. 2.

14 represents a tubular shell of an internal diameter to be placed over and surround the lower portion of the peripheral wall 9' of the pot and to enclose the legs 8 above the respective feet 10.

Slots or openings 16 are thus provided below the lower edge of the shell for the admission of air to support combustion of the lamp fuel, and outlet openings, as 17, are provided between the legs 8 for the discharge of smoke and other gaseous combustion products. 18 represents a handle provided on the shell for raising it to give access to the stove 12 to light and regulate the same, and also for replenishing the oil.

The standard 6 serves as a holder for a roll 19 about which is wound the article, such as thread 20, which is to be tarred. The roll is supported for rotary motion upon a pin 21 which is withdrawable from the standard. 65 The other standards, 7, as shown, consist of two companion members each having a bearing for a crank shaft 22 held in place by means of caps 23 which are secured by removable pins 24. 25 represents a reel 70 mounted upon said shaft to rotate therewith for winding the thread about the reel by turning the same by means of the shaft's crank 26, employed as a handle.

Secured to the inner surface of the peripheral wall of the pot at that side nearest the standard 6 is a bracket having two vertically spaced apertured arms 27 through which extends for vertical movement the shank 28 of a thread guide. The upper end of the shank 80 above the bracket is formed with an eye produced by bending such shank end spirally, as at 29, permitting the thread to be entered helically into the eye. Below said bracket the shank of the guide is extended as a horizontal arm 30 which terminates in a loop 31 to receive the thread therein. The thread withdrawn from the roll is passed or threaded through both the eye and loop elements of the guide when the guide, for the purpose, is held 85 by the operator in the elevated position in which it is indicated by dotted lines X in Fig. 2, after being thus threaded the guide is pushed downwardly into the operating position in which it is represented by full lines 90 in the referred to view, whereby the thread in proximity to the loop 31 is caused to be submerged in the tar. The thread is drawn from the roll 19 and through the guide when 95 the thread is wound about the reel 25. A pair 100

of pressure blocks 32, preferably of rubber or a composition containing rubber, are employed above the pot, between which blocks the thread is caused to pass after leaving the tar to rid the thread, by squeezing, of excess tar which falls into the pot.

As shown, the blocks 32 are provided within in a holder of a frame 33 which is rigidly connected as by means of a bracket 34 to the pot. Said blocks, moreover, are located between an end 35 of said holder and a pressure plate 36 which is regulated by means of an adjusting screw 37 operable in a screw threaded hole provided in the other end 38 of the holder.

In operation, the thread wound about the reel 25 withdraws the thread from the roll 19, whence it passes through the guide eye 29 and loop 31 whereby it is dipped in the molten tar contained in the pot, and thence between the resilient blocks 32 which serve to wipe superfluous tar from the thread. The reel may be removed from the standards 7 after removing the shaft 22 therefrom.

What I claim is,—

1. The combination, in a device for tarring thread and the like, of a tar-containing pot, means to retain the tar in said pot in a state of fluidity, a supply roll mounted for rotation at one side of the pot, a reel mounted for rotation at the other side of the pot, a thread guide freely mounted for vertical movement and adapted to submerge and elevate the thread within and from the tar in the pot, and pressure means disposed between said guide and the reel for removing superfluous tar from the thread, said thread guide comprising a rod member configured to present a shank terminating in an eye at the top and a loop at the bottom, the thread being adapted to pass successively through said eye and the loop.

2. In a device for tarring thread and the like, a tar-containing pot, a bracket disposed at one side of the pot, a thread guide freely mounted for vertical movement in said bracket for submerging and elevating the thread within and from the tar in the pot, and pressure means carried by said pot at its opposite side and through which the thread is adapted to pass for removing superfluous tar from the thread, said thread guide comprising a rod conformed to present a shank slidable in said bracket and bent at its opposite extremities to respectively present an eye above and a loop below the bracket, the thread being successively passed through said eye and the loop.

3. In tarring devices as defined in claim 2, wherein the thread is adapted for insertion and removal from said eye and loop without detaching the guide from the pot.

4. In a device for waterproofing thread and the like, a pot for containing a waterproofing liquid, an apertured bracket disposed at one

side of the pot, a thread guide supported for vertical movement in said bracket for submerging and elevating the thread within and from the liquid in the pot, said thread guide comprising a rod, the shank of which is slidable in the aperture of said bracket and the opposite ends being looped to provide thread-receiving eyes, the upper of said eyes being disposed in the approximate vertical axis of the rod shank and the lower of said eyes being disposed in offset disposition of said axis, the thread being passed successively through the eye above and the eye below the bracket with the offset disposition of the lower eye serving to yieldably retain the rod in its lowermost position to submerge the thread responsive to the binding of the sliding shank in the bracket.

Signed at Seattle, Washington, this 9th day of January, 1929.

RICHARD GREVSTAD.
